UNITED STATES PATENT OFFICE.

WILLIAM A. HOUCK, OF READING, PENNSYLVANIA.

COP-MOUNTING.

1,377,416.

Patented May 10, 1921.

Application filed September 21, 1920. Serial No. 411,746.

To all whom it may concern:

Be it known that I, WILLIAM A. HOUCK, a citizen of the United States, residing at Reading, in the county of Berks and State of Pennsylvania, have invented certain new and useful Improvements in Cop-Mountings, of which the following is a specification.

My invention relates to cop mountings for knitting machines or the like, and it consists 10 in improved means for supporting the unwinding thread so as to prevent any tangling or breakage thereof, as fully described in connection with the accompanying drawing and clearly defined in the claims.

15 Figure 1 is a sectional elevation showing the application of my invention to a known cop arrangement indicated.

Fig. 2 is a plan view of one of the four thread-supporting segment bars preferably 20 employed.

Fig. 3 is a cross-sectional view of the cup on the line 2—2 of Fig. 1; showing the retracted positions of the thread-supporting bars though only one of them is fully illustrated; and indicating the operative position in dotted lines.

Fig. 4 is a fragmentary view looking in the direction of the arrow in Fig. 3, to show the spring employed to press inwardly upon 30 the overlapping portions of two of the bars.

The drawing indicates an ordinary conical inner tube or quill 3 upon which the thread is wound, fitting upon a support 4 fixed to a central support-spindle 5, 5^a in the 35 base plate 6 so that its unwound lower end 7 below the wound thread indicated by lines 3^a extends into an encircling cup 8 on the base plate; this construction and arrangement being shown in my prior Patent No. 40 1,169,539.

The particular purpose of my invention is to provide such a support for loosened thread, underneath the winding 3^a, as will prevent its sagging and becoming entangled 45 and broken, as is ordinarily liable to occur. To this end I arrange for tightly closing the small annular space left between the inserted unwound quill end 7 and the wall of the cup 8, by means of a plurality of segment bars 10, as illustrated in Fig. 2; these being radially movable in the cup 8 so as to either bring the inner curve 11 thereof into close contact with the outer surface of the quill portion 7 during operation of the cop, 55 as indicated by the dotted circle 11^a Fig. 3 or

to bring the outer curve 12 thereof against the inner wall of the ring 25 in cup 8 so as to provide space for introducing or withdrawing the cop.

Preferably four similar segment bars 10 60 are employed, each provided with an intermediate pivot hole 13 and with a short arm 14^a and a long arm 14 somewhat exceeding a quarter circle; so that when pivotally mounted in pairs upon the operating pivot- 65 pins 15, 15 hereafter referred to, their slightly overlapping arms 14, 14 will entirely close the annular space around the unwound quill portion 7, when they are swung inward to the line 11^a, Fig. 3; while in with- 70 drawn position, as shown in the drawing, they will provide annular space for free insertion and withdrawal of the cop.

Each of the oppositely arranged pivot- 75 pins 15 extends upward through enlarged openings 16 in the base plate 6 and the bottom of the cup 8, and forms part of an operating lever 17 pivoted at 18 to a bracket 19 under the plate 6. These pins are normally swung radially inward, as shown, by 80 means of a spring 20, but are movable outward to the positions shown in the drawing, by merely pressing together the lever ends 21. The segment bars 10, as previously 85 stated, are swung inward and outward with the pivot pins 15, 15, being pivoted thereon and carried upon a flanged ring 25 in the cup 8, as shown.

The segment bars 10 are free to turn upon their intermediate pivot connections 13 to 90 the pins 15, so as to adjust themselves to the respective curvatures of the unwound quill portion 7 and of the cup wall; but as the oppositely extending portion 14^a is made shorter than the quarter-circle arm 14, as 95 shown, I preferably employ a spring 30, fixed to the flanged ring 25 and having an upwardly turned end 31 as indicated in Figs. 3 and 4, to normally press the longer arms 14 inward so as to equalize their contact 100 with the quill portion 7. The detail construction specifically set forth may be readily modified within the scope of the invention as defined in the claims.

What I claim is:

1. In combination with a base plate carrying a central cop support and a cup encircling the lower portion of said support; radially movable pivot pins extending into said cup, and thread-supporting bars radi- 110

ally movable with said pins into and out of contact with the lower portion of a mounted cop.

2. In combination with a base plate carrying a central cop support and a cup encircling the lower portion of said support; thread-supporting segment bars mounted in said cup, and radially-swinging operating levers for said bars pivoted below said plate and having bar-engaging pivot pins.

3. In combination with a base plate carrying a central cop support and a cup encircling the lower portion of said support; thread-supporting segment bars mounted in said cup, operating levers for said bars pivoted below said plate and having bar-engaging pivot pins, and spring means for normally pressing said bars into contact with the lower portion of a mounted cop.

4. In combination with a base plate carrying a central cop support and a cup en-

circling the lower portion of said support; thread-supporting segment bars mounted in said cup, operating levers for said bars pivoted below said plate and having bar-engaging pivot pins, and separate springs operative upon said levers and bars respectively to press the latter into contact with the lower portion of a mounted cop.

5. In combination with a base plate carrying a central cop support, and a cup encircling the lower portion of said support; oppositely arranged radially movable pivot pins extending into said cup, four thread-supporting segment bars intermediately pivoted in pairs upon said pins, and spring means for normally pressing said bars into contact with the lower portion of a mounted cop.

In testimony whereof I affix my signature. 40

WILLIAM A. HOUCK.
